(57) **CLAIM**

The ornamental design for a shotgun shell cigarette lighter, as shown and described.

DESCRIPTION

FIG. 1 is a perspective view of the shotgun shell cigarette lighter with the lid open;

FIG. 2 is a top plan view of the shotgun shell cigarette lighter with the lid closed;

FIG. 3 is a side view thereof;

FIG. 4 is a bottom plan view thereof;

FIG. 5 is a rear view thereof;

FIG. 6 is a front view thereof;

FIG. 7 is a top view of the shotgun shell cigarette lighter with the lid open;

FIG. 8 is a side view thereof;

FIG. 9 is a rear view thereof; and,

FIG. 10 is a front view thereof.

The broken line environmental showing is for illustrative purposes only and forms no part of the claimed design.
